UNITED STATES PATENT OFFICE.

MICHAEL J. SULLIVAN, OF CHICAGO, ILLINOIS.

DESIGN FOR A BADGE.

SPECIFICATION forming part of Design No. 24,443, dated July 2, 1895.

Application filed May 20, 1895. Serial No. 550,001. Term of patent 3½ years.

To all whom it may concern:

Be it known that I, MICHAEL J. SULLIVAN, of Chicago, in the county of Cook and State of Illinois, have invented and produced a new and original Design for a Badge or Insignia, of which the following is a specification, reference being had to the accompanying drawing, forming a part thereof.

The figure illustrates my design, which consists of sixteen disks or nuggets A, of silver, (color,) arranged, as shown, to represent the outlines of the wooden portion of a spinning-

top, with a gold (color) nugget B, suspended from or attached to the lowest of the silver disks or nuggets to represent the spike or metal point of the top.

What I claim is—

The design for a badge or insignia herein shown and described.

MICHAEL J. SULLIVAN.
